UNITED STATES PATENT OFFICE.

HAROLD D. ELFRETH, OF PHILADELPHIA, PENNSYLVANIA, ASSIGNOR, BY MESNE ASSIGNMENTS, TO H. S. B. W.-COCHRANE CORPORATION, OF PHILADELPHIA, PENNSYLVANIA, A CORPORATION OF PENNSYLVANIA.

STRAINER VALVE FOR FILTERS.

1,409,337.

Specification of Letters Patent. Patented Mar. 14, 1922.

Application filed January 28, 1919. Serial No. 273,546.

To all whom it may concern:

Be it known that I, HAROLD D. ELFRETH, a citizen of the United States, residing in the city and county of Philadelphia, State 5 of Pennsylvania, have invented new and useful Strainer Valves for Filters, of which the following is a specification.

My invention consists of a strainer valve for a filter embodying a body and a top 10 plate or cover therefor having between them an orifice or port which permits the flow of the water to be filtered into said body, said top plate being provided with means for positioning and retaining it on said body, 15 avoiding the use of screws therefor, and adapting said orifice or port to be enlarged automatically by outflowing water when the filter is being washed to cause sand or other matters that may have lodged in said orifice 20 or port to be removed therefrom.

The invention is satisfactorily illustrated in the accompanying drawing, but the important instrumentalities thereof may be varied, and so it is to be understood that the 25 invention is not limited to the specific details shown and described.

Figure 1 represents a vertical section of a strainer valve embodying my invention.

Figure 2 represents a bottom plan view of 30 the top plate of the device.

Figure 3 represents a section of a member of the top plate detached, on line 3—3 Figure 2.

Similar numerals of reference indicate 35 corresponding parts in the figures.

Referring to the drawings,

1 designates the body of the strainer valve which is attachable to a filter, strainer, manifold, or diaphragm, and 2 the top plate 40 or lid therefor, the latter being adapted to rise and lower in its operative position.

On the underside of said plate are the lugs 3 formed therewith or secured thereto at intervals which are adapted to engage 45 the inner side of the upper portion of said body so as to properly locate said plate on said body, prevent displacement of said plate, and guide the latter in its vertical movements, it being noticed that the bottom 50 of said plate is raised from the top of said body as to form the port or annular orifice 4 between said body and plate for the ad-

mission of water into the former from a filter bed in the direction of the left hand arrows in Figure 1.

In order to retain the plate raised from the body and prevent said orifice or port from closing, the lugs 3 are formed with outwardly laterally projecting flanges 5 which are adapted to rest on the top edge 60 of the rim of the body while the outer faces of the lugs proper form shoulders with said flanges, and so the lugs proper are adapted to enter the body 1 adjacent to the inner side of the upper portion thereof, the descent of the plate being as is evident limited by said flanges abutting the top edge of the body as stated, the positioning of the plate thus being adjusted and the orifice or port 65 70 75 80 85 90 95 100 preserved in its open condition.

Pendant from the centre of the underside of the plate 2 and secured thereto or formed therewith is the ear or eye 6 which enters the body 1 and has passed through it the transversely-extending pin or rod 7 whose 75 ends are secured to the side wall of the body 1, the diameter of the opening 8 of said eye being somewhat greater than that of the diameter or thickness of the pin 7 so that said opening has a clearance to permit the eye 80 and consequently the top plate to rise to an extent limited by said pin without actual displacement of said top plate.

By this provision the port or orifice 4 may be enlarged in vertical direction, so that 85 when the filter is being washed and water enters the body in reversed direction, that is, in the direction of the right hand arrows, it raises the top plate and the water flows out through the enlarged orifice or 90 port releasing and taking with it any sand or other foreign matters that may have lodged in said orifice or port and directing the water with said matters through and from the device.

When the outward flow of the water ceases, the top plate lowers to its adjusted position restoring the orifice or port in normal condition.

It will be seen that by the present construction of the members of the device, the objectionable screws heretofore used to guide and connect the top plate are dispensed with.

Having thus described my invention what I claim as new and desire to secure by Letters Patent, is:—

1. In a strainer for a filter, a body, a lid therefor, said lid and body being adapted to have between them a port, an ear depending from the interior of said lid and a transversely extending pin in said body connected with the side thereof and passing through an opening in said ear, said opening being of considerably greater diameter in vertical direction than that of said pin, whereby said ear is adapted to have a vertical play on said pin, thereby permitting the bodily ascent of said lid to cause the latter to open automatically said port to a greater extent than normally.

2. In a strainer for a filter, a body, a lid therefor, a guiding lug depending from the

interior of said lid adjacent to the inner wall of said body, said lug being formed with a flange which is adapted to be seated on the top of said body providing ports between said lid and body, an ear depending from the interior of said lid and having an opening in it, and a transversely extending pin in said body connected with the side thereof, and adapted to pass freely through said opening, the latter being of greater diameter in vertical direction than that of said pin, whereby said ear is adapted to have a vertical play on said pin to permit the lid to open automatically said port to a greater extent than normally.

HAROLD D. ELFRETH.
